US00D787952S

(12) **United States Design Patent** (10) **Patent No.:** **US D787,952 S**
Jacober et al. (45) **Date of Patent:** **** May 30, 2017**

(54) **CONTOURED NECK FOR A BEVERAGE CONTAINER**

(75) Inventors: **Mark A. Jacober**, Arvada, CO (US);
Howard C. Chasteen, Westminster, CO (US)

(73) Assignee: **Ball Corporation**, Broomfield, CO (US)

(**) Term: **14 Years**

(21) Appl. No.: **29/430,744**

(22) Filed: **Aug. 29, 2012**

(51) LOC (10) Cl. **09-02**

(52) U.S. Cl.

USPC **D9/772**

CLAIM

The ornamental design for a contoured neck for a beverage container, as shown and described.

DESCRIPTION

FIG. 1 is a front perspective view of a contoured neck for a beverage container;

FIG. 2 is a top plan view thereof; and,

FIG. 3 is a front elevation view thereof.

The broken lines shown represent unclaimed subject matter and form no part of the claimed design.

1 Claim, 2 Drawing Sheets
